UNITED STATES PATENT OFFICE.

PAUL RICHTER, OF CHEMNITZ, GERMANY.

MACHINE FOR GRINDING SLABS.

1,088,297.

Specification of Letters Patent. Patented Feb. 24, 1914.

Application filed July 28, 1913. Serial No. 781,637.

To all whom it may concern:

Be it known that I, PAUL RICHTER, a subject of the German Emperor, and resident of Dittersdorferstrasse 81, Chemnitz, Germany, have invented certain new and useful Improvements in Machines for Grinding Slabs, of which the following is a specification.

My invention relates to improvements in grinding machines for slabs of natural and artificial stone and its object is to provide an arrangement for the continuous introduction of separate slabs to the grinding mechanism.

According to this invention various devices for setting and lifting the raw slabs and for removing the finished slabs are arranged in such a manner that a single lifting and lowering device serves successively in several apertures of the turntable work-table for pressing the superposed workpiece against an upper grinding disk. With this arrangement it is now possible to introduce slabs in uninterrupted succession to the circulating grinding disk, to remove the ground slabs and to regulate the pressure at will, while at the same time little attendance is required and the output is great.

The invention is shown in the several figures of the accompanying drawings, in which—

Figure 1 is a side elevation, partly in section, of the machine. Fig. 2 is a section taken on the line I—I of Fig. 1. Fig. 3 is a vertical section drawn to a larger scale of the grinder. Fig. 4 is a face view of the upper part of the machine according to Fig. 1.

The bevel wheel 1 on the driving shaft 1¹ rotates by means of a bevel wheel 2 the vertical shaft 3 which carries at its lower screw-threaded end 4 a bearing block 5 in the swinging nave of which is mounted the planet-wheel 7 for driving the grinding disk 12. The stationary wheel 8, with which the planet-wheel engages, is mounted with a long sleeve in the lower arm of the frame and is prevented from turning by a slot and screw engagement 10 and 11 respectively.

The planet motion of the grinding disk 12 insures for a uniform and smooth surface being obtained over the entire slab. The grinding disk 12 is fixed to an iron plate 13 which connects it with the carrier 14. The carrier 14 has an open upwardly directed flange 15 into which a constant stream of

water is delivered from a suitably jointed pipe 15¹, the water passing through openings 16 in the carrier 14 and the plate 13 to the surface being ground.

To compensate for the constant wear of the grinding disk, an adjusting device for the vertical shaft 3 is provided which consists in a spindle 17, operated by the hand-wheel 18 (Figs. 1 and 4), coiled spring 19 and a screw nut 20 for regulating the tension of the spring 19 when the shaft 3 is shifted. The long sleeve of the stationary wheel 8 in which the shaft 3 is mounted, moves down with the latter and its wheel 8 by reason of plate 21 fast on the planet-wheel 7, see Fig. 3.

The round table 22, which turns on a central pivot in ball-bearing and upon a lower ball 23, and which can be easily turned by means of handles 24, is here shown by way of example with four openings 25 which form passages for a slightly smaller lifting plate 26 provided with four pins 27 for carrying the workpiece and pressing same against the grinding disk 12. The lifting plate 26 is operated by a handlever 32 which at 31 is pivotally connected to the vertical stem 30 of the plate 26. The table 22 is locked during the grinding operation by a bolt 38 entering one of the notches 39.

To prevent the slabs, loosely supported upon the pins 27 of the plate 26, from lateral displacement during the grinding process the table has slots 28 near each side of the openings 25 in which four guards 29 can be adjusted and fixed so as to hold the workpiece. The two-armed hand-lever 32 carries at its forward end a weight 33 the shifting of which will regulate the pressure of the workpiece against the grinding disk.

For turning the table 22 after a slab has been finished, the weighted lever 32 is to be lifted until a spring-actuated bolt 34 enters a notch 35 and thereby keeps said lever 32 up and the lifting plate 26 lowered. A rod 36 is then pulled so as to withdraw, through the intervention of a double lever 37, the locking bolt 38 from the notch 39 and allow the table to be turned by means of one of the handles 24 until the next notch 39 engages with the locking bolt 38. The spring 40 then keeps the table automatically locked. Below the table underneath the grinding appliance there is provided a water collecting bowl 41 with outlet pipe 42 for the discharge of waste water. In consequence of

the multi-supporting places for the slabs upon the table, according to this arrangement, continuous working can be carried out, that is to say that while one slab is being ground a previously finished slab can be removed at one side of the machine and a fresh slab for grinding can be placed on the table at the other side thereof.

What I claim as my invention and desire to secure by Letters Patent is:—

1. Machine for grinding slabs, comprising in combination a machine-frame, a table formed with circularly disposed apertures and turnable in said frame, a grinding disk arranged in said frame, means for turning said grinding disk, a plate for holding the workpiece and adapted to traverse any of said apertures, adjustable guard rails surrounding the apertures in said table and adapted to prevent the workpiece from lateral displacement, a stem vertically guided in said machine frame and carrying said plate, a hand-lever for moving said stem, a spring actuated bolt for holding said hand lever in its uppermost position, a locking bolt engaging into notches provided in the rim of said table, and lever-connection to withdraw said bolt from said notches, substantially as set forth.
2. Machine for grinding slabs, comprising in combination a machine-frame, a table

formed with circularly disposed apertures and turnable in said frame, a grinding disk arranged in said frame, means for turning said grinding disk, a plate for holding the workpiece and adapted to traverse any of said apertures, guard rails adjustable in slots and surrounding the apertures in said table and adapted to prevent the workpiece from lateral displacement, a stem vertically guided in said machine frame and carrying said plate, a hand-lever for moving said stem, a spring actuated bolt for holding said hand lever in its uppermost position, a locking bolt engaging into notches provided in the rim of said table, and lever-connection to withdraw said bolt from said notches, substantially as set forth.

In testimony whereof I have hereunto signed my name this 9th day of July, 1913, in the presence of two subscribing witnesses.

PAUL RICHTER.
